United States Patent Office

Des. 187,865
Patented May 10, 1960

187,865

COMBINED MAP GLOBE AND SUPPORT THEREFOR

Victor A. Peterfil, Oak Park, Ill., assignor to Replogle
Globes, Inc., Chicago, Ill., a corporation of Illinois

Application January 28, 1959, Serial No. 54,365

Term of patent 14 years

(Cl. D25—1)

Fig. 1 is a perspective view of the combined map globe and support therefor embodying my design; and

Fig. 2 is a side elevational view thereof.

The essential features of the combined map globe and support therefor reside in the portion shown in solid lines.

I claim:

The ornamental design for a combined map globe and support therefor, substantially as shown and described.
